[57] CLAIM

The ornamental design for a racecar tape measure, as shown and described.

DESCRIPTION

FIG. 1 is a perspective view of a first preferred embodiment of my racecar tape measure;

FIG. 2 is a top plan view thereof;

FIG. 3 is a left side elevation view thereof;

FIG. 4 is a right side elevation view thereof;

FIG. 5 is a rear side elevation view thereof;

FIG. 6 is a front side elevation view thereof;

FIG. 7 is a bottom plan view thereof;

FIG. 8 is a perspective view of a second preferred embodiment of my racecar tape measure;

FIG. 9 is a perspective view of a third preferred embodiment of my racecar tape measure;

FIG. 10 is a top plan view thereof;

FIG. 11 is a left side elevation view thereof;

FIG. 12 is a right side elevation view thereof;

FIG. 13 is a rear side elevation view thereof;

FIG. 14 is front side elevation view thereof;

FIG. 15 is a bottom plan view thereof;

FIG. 16 is a side elevation view of the fourth preferred embodiment;

FIG. 17 is a side elevation view of the fifth preferred embodiment; and,

FIG. 18 is a side elevation view of the sixth preferred embodiment.

The broken line showing is for illustrative purposes only and forms no part of the claimed design.
